UNITED STATES PATENT OFFICE.

THEODORE L. VALERIUS AND OLAF LARSEN, OF FORT ATKINSON, WISCONSIN, AS
SIGNORS TO THE CREAMERY PACKAGE MFG. COMPANY, OF CHICAGO, ILLINOIS, A
CORPORATION OF ILLINOIS.

CONVEYING MECHANISM FOR CAN WASHERS.

Application filed June 30, 1919. Serial No. 307,821.

To all whom it may concern:

Be it known that we, THEODORE L. VALERIUS and OLAF LARSEN, citizens of the United States, residing at Fort Atkinson, in the county of Jefferson and State of Wisconsin, have invented certain new and useful Improvements in Conveying Mechanism for Can Washers, of which the following is a specification.

10 This invention relates to the art of cleaning milk cans and the like, and the covers therefor; and the general object of the invention is to cleanse the cans and covers thoroughly with a minimum amount of hand labor and at a considerable rate of speed. It is also an object of the invention to dry the cans and covers after they have been washed, rinsed and sterilized.

While the invention is herein shown as embodied in a machine for treating cans of the well known type used for the shipment of milk and cream, it will be understood that the invention may be applicable to the handling of other large metallic containers.

20 In the accompanying drawings Figure 1 is a front elevation of an apparatus embodying the features of our invention, the front cover being removed. Fig. 2 is a fragmental top plan view of the apparatus. Fig. 3 is an elevation of the receiving end of the apparatus. Fig. 4 is a fragmental sectional view of the can-forwarding device, the view being taken in the plane of dotted line 4—4 of Fig. 5. Fig. 5 is a fragmental plan view 25 of the can-forwarding device. Fig. 6 is a vertical sectional view taken in the plane of dotted line 6—6 of Fig. 1, the hinged door between the washing compartment and the rinsing and steam compartment being partially broken away. Fig. 7 is a view taken 30 in the plane of line 7 of Fig. 2, showing the inverter. Fig. 8 is a front view of the inverter. Fig. 9 is a transverse vertical section taken in the plane of line 9—9 of Fig. 45 1, the door that closes the exit from the rinsing and steam compartment being partially broken away. Fig. 10 is a view of the drier, taken in the plane of line 10 of Fig. 1. Fig. 50 11 is a front view of the drier, with parts broken away. Fig. 12 is a rear side elevation of the apparatus. Fig. 13 is a fragmental plan view of the can-forwarding device and steam-valve-operating device. Fig. 14 is a plan view of the device for forward-

ing detached covers, the view being divided 55 into two portions on account of limitations of space. Fig. 15 is a vertical transverse sectional view taken in the plane of line 15—15 of Fig. 14. Fig. 16 is an elevation of the receiving end of the cover-forwarding device, and Fig. 17 is a section on line 17—17 of Fig. 14. Fig. 18 (Sheet 3) is a top plan view of the receiving end of the machine, showing a can-controlled means for rinsing the cans with cold water.

The embodiment herein shown of the invention comprises a tank to contain a hot cleansing solution, a pump to draw the solution from said tank and deliver it to a jet head located above the tank, a tank containing clean hot rinsing water, a pump to draw water from the last mentioned tank and deliver it to a jet head located above the tank, a steam jet, a plurality of hot air jets, a can inverter, tracks extending above said jets, and means for moving the cans and covers upon said tracks into position above the various jets in succession. The tracks lead to the inverter where the sterilized and dried cans are inverted for inspection and removal.

While any suitable form of supporting framework and tank may be employed, there is herein shown a rigid framework comprising an elongated tank 1 divided by a partition 2 so as to provide a solution tank 3 and a rinsing tank 4. The tank 1 is supported upon legs 5. Brackets or bars 6 (Figs. 6 and 9) extend transversely of the tank 1. Upon the brackets 6 are mounted 90 brackets 7. Each bracket 7 is in the form of a partition having openings therein of suitable size and shape to accommodate the articles being treated, the tracks on which said articles travel, and the devices for moving the articles. Upon the brackets 7 is mounted a deck frame 8. The parts just described are rigidly secured together and constitute a supporting framework for the tracks, the article-forwarding devices and 95 other parts of the apparatus.

The front of the apparatus, i. e., the space between the tank 1 and the deck frame 8, is closed by a removable cover (not shown). The rear side of said space is closed by a 105 wall 8^a (Fig. 12). One of the partitions 7 is located approximately in the vertical plane of the partition 2, and thereby serves

to keep the cleaning solution from splashing into the tank 4. If desired, a door 7^a may be hinged to each partition 7 to close the opening through which the cans travel, 5 said door being arranged to be swung aside by a can passing through the opening, and being returned by gravity to normal position.

It will be seen that the space bounded by 10 the tank 1, the front cover, the deck frame 8, and the rear wall 8^a is divided by the middle partition 7 into a washing compartment and a rinsing and steaming compartment.

Each of the tanks 3 and 4 is provided 15 with an overflow 9 (Figs. 6 and 9).

A pump 10 is arranged to draw the solution from the tank 3 through a pipe 11 and discharge the liquid through a pipe 12 which carries a jet head 13. The head 13 is provided 20 with openings 14 (Fig. 2) through which the solution is discharged into the cans A traveling above the jet head, and is also provided with openings 15 arranged to discharge the solution into can covers B 25 traveling past the jet head.

A pump 16 is arranged to draw hot water from the tank 4 through a pipe 17 and discharge the water through a pipe 18 that carries a jet head 19 which is similar to the 30 jet head 13. The pumps 10 and 16 are continuously driven by any suitable means. The jet heads 13 and 19 thus operate continuously. When cans and covers are not opposite the orifices of the jet heads 13 and 35 19, the jets are projected against the deck frame and the removable front cover, whence the liquid is deflected in all directions, thus cleaning the cans and covers externally. In addition thereto, we provide 40 two spray pipes 12^a and 18^a (Fig. 1) connected to pipes 12^b and 18^b, respectively, which in turn are connected to the pipes 12 and 18, respectively, the pipes 12^a and 18^a being located at one side of the path of the 45 cans and covers and being perforated at the side toward the cans and covers so as to spray washing solution and rinsing water, respectively upon the cans and covers.

Any suitable means may be provided for 50 supplying water to the tanks 3 and 4 and for heating the contents of said tanks.

The cans are passed through the machine in an inverted position so that the liquids discharged into the cans shall drain into the 55 tanks 3 and 4. The cans are inclined at such an angle that but little water shall accumulate upon the depressed bottoms of the cans, and thus reduce the amount of solution which is transferred to the tank 4.

60 The means for supporting the cans in their passage through the machine comprises a bar 20 against which the can bodies rest, and two bars 21 against which the mouths of the cans bear. These bars are 65 secured to the brackets 7 and form a track

upon which the cans may be advanced through the machine. 22 is a stop bar extending along the path of movement of the cans.

Covers which are connected to their respective cans by a link C (Fig. 6) travel through the machine upon a track consisting of bars 23 and 24. 25 are bars located in position to prevent displacement of the covers. The bars 23, 24 and 25 form a channel through which the covers travel in an inclined position, the angle of inclination being such that no water will accumulate in the covers.

The bars 20 to 25, inclusive, extend from a 80 point sufficiently forward of the compartment 3 so that cans and covers may be placed thereon.

After passing the rinsing jet head 19 the cans pass a means for supplying steam to 85 the cans, as, for example, a pipe 26 (Figs. 1 and 9), said pipe being arranged to discharge steam into the cans and being connected to a suitable steam supply. The pipe 26 may have a branch 26^a (Fig. 9) to discharge steam into the covers.

After passing the steam jets 26 and 26^a the cans and covers travel over a drying means. In the present embodiment of the invention, said drying means comprises an 90 insulated casing 27 (Figs. 10 and 11) located beneath the track for the cans, said casing containing steam coils 28. Air is supplied to the casing 27 by any suitable means, as for example, a blower 29 (Fig. 10), the discharge of said blower being connected to a conduit 30 which communicates with the lower part of the casing 27. The casing contains baffle plates 31 (Fig. 11) arranged so as to compel a circuitous flow 100 of air through the casing. Upon the upper walls of the casing are mounted a suitable number of nipples 32 arranged to discharge hot air into the cans. Herein are shown three such nipples placed along the path of 105 travel of the cans. 32^a are openings to discharge hot air against the covers.

If desired, the steam coils 28 may discharge steam and water of condensation through the pipe 26, that being the arrangement herein shown.

After the cans have passed the drier, they are received in an inverter 33. The form of inverter selected for illustration comprises a base 34 supported upon a pedestal 35, and two walls 36 and 37 mounted on the base 34. The wall 36 extends transversely of and rearwardly from the can track. The bar 20 terminates at the wall 36. The bars 21, 22, 23, 24 and 25 continue past the wall 36 a distance somewhat greater than the diameter of a can, the bars 21 and 22 being secured to an end guard or stop wall 38 extending transversely of the can track. In the space between the verti- 125 130

cal planes of the walls 36 and 38 is a shelf 39 (Fig. 7) the forward end of which is pivotally supported at 40. The shelf 39 is supported upon a buffer consisting of a cross-bar 41 attached to two rods or bolts 42 which are vertically slidable in guide openings in a flange 43 on the base 34. Expansion springs 44 surround the rods 42 between the flange 43 and the cross-bar 41.

10 The normal position of the buffer is determined by nuts 45 on the ends of the rods 42 below the flange 43.

46 is a curved plate secured to the shelf 39 at the side toward the guard wall 38.

15 This plate, however, is not essential.

Upon the base 34 is a horizontal series of rollers 47 (Fig. 2) which is continued in an inclined roller-runway 48. As shown in Fig. 7, the shelf 39 is above the plane of the roller bed 47. The shelf is shorter than the cans.

20 When a can is moved beyond the end of the bar 20, it topples over rearwardly onto the shelf 39 and rights itself, the can fulcruming on the rear edge of the shelf and coming to rest with its lower end standing on the rollers 47 between the wall 37 and the rear edge of the shelf 39.

25 The means for moving the cans and covers through the machine comprises two parallel slide bars 49 and 50. The bar 49 is mounted for rectilinear reciprocation in guides 51 formed upon the brackets 7. The slide bar 50 is mounted to slide upon surfaces 52 on the brackets 7. The bar 50 is connected to the bar 49 by means of pivoted links 53. To the bar 50 are fixed dogs 54, the forward ends of said dogs being made concave upon opposite sides to conform in a general way to the cylindrical bodies of the cans. The dogs 54 are spaced apart so that a single can may lie in the space between two adjacent dogs.

30 The means for reciprocating the bars 49 and 50 comprises a bracket 55 (Fig. 5) secured to the slide bar 50 and arranged to engage a stop 56 on the slide bar 49 when the links 53 are at right angles to the bars 49 and 50 (see Fig. 13). A connecting rod 57 is pivoted at one end to the bracket 55 and at its opposite end to one arm of a lever 58 (Fig. 1) which is pivotally mounted at 59 upon the deck frame 8. The other arm of the lever 58 is connected by means of a connecting rod 60 to a wrist pin upon a spur gear wheel 61. The gear wheel 61 is fixed upon a shaft 62 which is mounted in bearings on two brackets or standards 63 fixed to the deck frame 8. The gear wheel 61 meshes with a pinion 64 which is fixed upon a shaft 65 (Fig. 2) carried by the standards 63. On the shaft 65 are fixed two spur gear wheels 66 and 67 which may be of different diameters, said gear wheels meshing, respectively, with pinions 68 and

69 which are loose on a shaft 70 carried by the standards 63. On the shaft 70 is a slideable clutch member 71 adapted to clutch either of the pinions 68 and 69 to the shaft 70. Any ordinary means may be provided for shifting the clutch member 71. Suitable means, including a pulley 72 and spiral gearing 73, is provided for driving the shaft 70.

Referring to Figs. 5 and 13: By reason of the link connection between the sliding bars 49 and 50, the bar 50 has a lateral and endwise movement into engagement with a row of cans resting upon the bars 20, 21 and 22, the row of cans being advanced one step in such lateral and endwise movement of the bar 50. At the beginning of the feed stroke, the bar 50 alone moves, but after the bar 50 has moved laterally into can-engaging position, both bars 35 slide by reason of the contact of the bracket 55 with the stop 56. When the movement of the bar 50 is reversed, it moves laterally on the guide surfaces 52, thus carrying the dogs 54 away from the cans, after 90 which the continuing movement of the bar 50 causes the bar 49 also to slide by reason of the link connections between the slide bars. The paths of movement of the dogs 54 are indicated by dotted lines *a* in Fig. 5. 95 Preferably, the bar 50 moves laterally just far enough to lift the cans out of contact with the bar 20 so that the cans shall not slide in contact with said bar 20.

The jet heads 13 and 19 and the hot-air nipples 32 are continually active, but it is not desirable to allow the steam jets 26 and 26^a to play except when a can and a cover are in register with or passing the steam jets. Therefore we provide a valve 100 74 (Figs. 1 and 13) in the steam supply pipe 74^a. This valve controls the supply of steam to the coils 31 and the jets 26 and 26^a, said valve having a stem 75 that lies in the path of an arm 76 pivoted at 110 77 on the bar 49. A spring 78 normally holds the arm 76 out of position to strike the end of the stem 75. An arm 79 which is rigid with the arm 76 projects into the path of movement of the cans so as to be 115 swung aside by a can which is being placed above the jet 26. In such movement of the arm 79, the arm 76 is swung into position to strike the end of the valve stem 75, whereby the valve 74 is opened to admit 120 steam to the coils 31 and the jets 26 and 26^a.

Means has been provided for cleaning covers B which are not attached to cans. This means comprises an elongated casing 81 (Fig. 6) supported in the rear portion of the machine by the brackets 7, and extending parallel with the path of travel of the cans. The forward end of the casing 81 is open for some distance along its upper and front sides to receive the covers. The 125 130

framework of the casing 81 includes an angle bar 82 (Fig. 15) which serves to support the upper rim of an endless chain 83 constituting a conveyer for the covers.

5 Said chain runs around sprocket wheels 84 and 85 located at opposite ends of the casing 81. (See Fig. 1.) The wheel 84 is fixed upon a shaft 86 on which is mounted a sprocket wheel 87 (Fig. 12). A chain

10 88 runs over the sprocket wheel 87 and a sprocket wheel 89 fixed on a shaft 90 which is supported by the deck frame 8. The shaft 90 is driven from the shaft 62 by means of a chain 91 running over sprocket wheels on said shafts.

15 In the casing 81 are two guide bars 92 and 93 which cooperate with the rear wall of the casing to hold the covers in an approximately vertical plane. The chain 83 supports the cylindrical portions of the covers.

20 As the covers travel through the casing 81 they are subjected to two jets of the cleansing solution. A pipe 94 (Fig. 12) is connected to the pipe 12^b and supplies solution to two branch pipes 95 (Fig. 2) that communicate with the interior of the casing 81 through rearwardly directed ducts 96 (Fig. 14). It will be seen that the jets 25 are delivered against the inner sides of the covers (i. e., the sides that fit against the cans) and that during the intervals between the passage of covers the jets strike the forward wall of the casing 81 and are deflected 30 in all directions, thus thoroughly cleaning all sides of the covers. Vertical baffle plates 97 extend transversely of the casing 81 in front of the path of the covers. These baffle plates serve to keep the jets that strike 35 the front wall of the casing from splashing into the adjacent tank 3 or 4, and also serve to deflect the spray against the covers. The baffle plates also act as supports for the guide bars 92 and 93.

40 45 After passing the solution jets 96, the covers are rinsed by means of jets of clean water discharged against the inner sides of the covers through rearwardly-directed ducts 98 (Fig. 14). Water is supplied to the ducts 98 through pipes 99 and 100.

50 As shown in Figs. 6 and 9, the lower side of the casing 81 is open to permit water to drain into the tank 1.

55 After passing the rinsing jets 98, the covers are sterilized by a steam jet 101 which is connected by means of a pipe 101^a (Fig. 12) to the steam supply pipe 74^a at a point ahead of the valve 74 so as to be in constant communication with the source of supply 60 except when the valve 102 is closed.

65 The discharge end of the casing 81 is open at its rear side, as shown in Figs. 12 and 15, in order that an operator stationed there may remove covers one by one and place them upon cans turned right side up by the in-

verter. As indicated in Fig. 14, the guide bar 92 is bent rearwardly so as to cause the covers to tilt rearwardly, the covers resting against a pipe 103 that extends along the casing. The side of the pipe 103 toward the 70 covers has perforations 104 for the discharge of hot air against the covers. The pipe 103 is connected to the upper portion of the casing 27 through a pipe 105.

The rear end of the casing 81 is closed by 75 a bar 106.

The supply of cleaning solution to the jets 12^a and 96 is controlled by valves 107 and 108 (Fig. 12). The supply of rinse water to the jets 18^a and 98 is controlled by valves 80 109 and 110.

The steam and vapors may be conducted away from the apparatus by suitable piping (not shown) connected to the exhaust hood 111.

85 In operation, a workman places cans in inverted position upon the bars 20, 21 and 22 within reach of the forwarding bar 50. If the covers are linked to the cans, they rest upon the bars 23 and 24. Loose covers 90 are placed in the casing 81, through which they are advanced by the continuously moving chain 83. The rate of travel of the loose covers is approximately the same as that of the cans. A workman is stationed at the 95 discharge end of the machine to place covers on the cans and start them down the roller chute 48.

95 Referring to Fig. 18 (Sheet 3): For most efficient results, the machine is placed near 100 the milk-receiving station. As fast as the cans are emptied, they are placed upon the can track, where they have ample time to drain before entering the washing compartment. A drain table 112 set beneath the receiving end of the can track catches the milk that drains from the cans. As the cans pass from over the drain table they may be rinsed with cold water. Herein is shown a cold water jet 113 arranged to 110 direct a stream of water into the can. Said jet is controlled by a valve 114 which may be generally similar to the steam valve 74. The valve 114 is arranged to be opened by a can-controlled device 115 which is similar 115 to the device 76, 79. Inasmuch as the jet 113 is outside the washing compartment, the rinsing water carries off most of the milk remaining on the inner surfaces of the can and prevents it from going into the 120 washing solution.

125 It will be understood that the invention is not limited to the precise arrangement and construction herein shown, and that various changes may be made without departing from the spirit of the invention, as set forth in the appended claims.

We claim as our invention:

1. In apparatus for cleaning cans, conveying mechanism having, in combination,

track means to support the mouths of the cans, a guide extending parallel with said track means against which the bodies of the cans lean, said guide being somewhat shorter than said track means, a shelf onto which the cans fall when advanced beyond the end of said guide, said shelf being shorter than a can, and a platform below the level of said shelf to receive the can as it 10 fulcrums on the end of said shelf.

2. In apparatus for cleaning cans, conveying mechanism having, in combination, a track upon which cans may lean in inclined position with the mouths of the cans lowermost, a bar extending parallel with said track and having means to engage the individual can bodies, said bar being located at the side toward which the cans lean, and means for actuating said bar to move the 20 cans along the track.

3. In apparatus for cleaning cans having covers attached thereto, conveying mechanism having, in combination, a track to support cans in an inclined position with the 25 mouths of the cans lowermost, a track extending parallel with and adjacent to the other track for supporting the covers, and means for moving cans along the first mentioned track.

30 4. In apparatus for cleaning cans having covers attached thereto, conveying mechanism having, in combination, a track to support cans in an inclined position with the mouths of the cans lowermost, a track extending parallel with and adjacent to the other track for supporting the covers, and can-moving means operating upon the individual cans to move them along the first mentioned track.

40 5. In apparatus for cleaning cans, conveying mechanism having, in combination, a track to support a series of cans in an inclined position with the mouths of the cans lowermost, and means engaging the individual cans of the series for moving them along said track.

50 6. In an apparatus for cleaning cans, conveying mechanism having, in combination, a track to support a series of cans in inverted position, and means engaging the individual cans of the series for moving them along said track, said means including a plurality of engaging members moving in a circuitous path and engaging said cans through a part of said path.

55 7. In an apparatus for cleaning cans having covers attached thereto, a track for inverted cans, a track extending parallel with and adjacent to the other track for supporting the covers, and means engaging the cans for moving the cans and covers along said tracks.

60 8. In an apparatus for cleaning cans, conveying mechanism having, in combination, a track forming an under support and a

lateral support for a series of cans in inclined position, a reciprocatory bar extending parallel with said track, and a plurality of members mounted on said bar for engaging and moving said cans along said 70 track, said bar being movable laterally into engagement with said cans to displace the cans from their lateral support on said track during the movement thereof.

9. Conveying mechanism having, in combination, a track for supporting a series of cans, a bar extending parallel with said track and provided with members to engage the cans, and means to move said bar laterally into engagement with cans, then to 80 move the bar longitudinally to advance the cans, then to move the bar laterally out of contact with the cans, and then to move the bar longitudinally to the starting position.

10. A conveyor having, in combination, a track to support cans, a bar mounted to have a longitudinal rectilinear movement parallel with the track, a second slide bar having a parallel link connection with the first slide bar, devices on the second slide bar to engage the can bodies, two parts on said bars adapted for engagement with each other when the second bar has moved on its parallel link connection away from the first bar to a predetermined extent, and means engaging the second bar for sliding both bars.

11. A conveyor having, in combination, a track to support cans in inclined inverted position, a bar mounted to have a longitudinal rectilinear movement parallel with the track, a second slide bar having a parallel link connection with the first slide bar, devices on the second slide bar to engage the can bodies, the cans leaning toward said second bar, two parts on said bars adapted for engagement with each other when the second bar has moved on its parallel link connection away from the first bar to a predetermined extent, and means engaging the second bar for sliding both bars.

12. In apparatus for cleaning cans, conveying mechanism comprising, in combination, a track for the undersupport of cans in inverted inclined position, a guide bar parallel to said track for the lateral support of said inclined cans, said guide bar terminating substantially short of the end of said track whereby cans passing from the end of said laterally supporting guide bar fall in the direction of their inclination, a platform to receive the falling cans, and means obstructing the lower ends of said cans in falling, causing the cans to be 120 reverted in upright position when received on said platform.

13. In apparatus for cleaning cans, conveying mechanism comprising, in combination, a track for the undersupport of cans 130

in inverted inclined position, a guide bar parallel to said track for the lateral support of said inclined cans, said guide bar terminating substantially short of the end of said track whereby cans passing from the end of said laterally supporting guide bar fall in the direction of their inclination, a platform to receive the falling cans, means obstructing the lower ends of said cans in

falling, causing the cans to be reverted in ¹⁰ upright position when received on said platform, and pushing means for advancing said cans from said platform onto a conveyor.

In testimony whereof we have hereunto set our hands.

THEODORE L. VALERIUS.
OLAF LARSEN.
